FLOOR CONSTRUCTION

Orril H. Hayes, Damariscotta, Maine

Application January 10, 1936, Serial No. 58,593

13 Claims. (Cl. 94—17)

This invention relates broadly to plastic floor construction, more particularly to floor construction of that type wherein various patterns are formed upon the surface of the floor. In floor construction of this general character, strips formed of brass or other material have been commonly employed for many years as a means for outlining or defining the patterns and also as a means for uniting or locking together the various sections of the plastic material which form the pattern.

One of the objects of this invention is to provide a new and improved strip for use in the formation of plastic floors of this character, such strips being known in the art as "terrazzo".

Another object is to provide in a terrazzo strip new and improved means whereby the sections of the plastic or cementitious composition of the floor pattern are locked or held together.

Another object of the invention is to provide in a terrazzo strip of this character new and improved means whereby the strip itself may be more firmly and securely tied or engaged with the plastic material forming the floor.

Another object of the invention is to provide a terrazzo strip which is partly adapted to be employed in already existing floor construction, such for instance, as a wooden floor which it is intended to over-lie with a floor of plastic composition.

Another object of the invention is to provide a new and improved terrazzo strip which may be more firmly and securely anchored to a wooden floor than as obtained in strips of this character as hitherto constructed.

A further object of the invention is to provide a terrazzo strip having a new and improved means for anchoring the strips together at their points of intersection, such that the patterns to be defined by the said strips may be readily laid out in the strip construction and whereby there is no danger of the strips which form the pattern becoming displaced or moved relatively to each other while the plastic material is being deposited within the structure formed by these strips.

Another object of the invention is to provide a terrazzo strip so constructed that when laid upon the surface underlying the terrazzo floor to be formed it will stand upon such surface in a vertical position or in a position at right angles to the floor to be surfaced unaided by any supporting means.

Another object of the invention is to provide a new and improved means for uniting or locking together the ends of adjacent strips such that a

straight line between said united strips is at all times maintained and the abutting strips will be held from relative displacement while the plastic material is being deposited in the patterns formed by the strips.

Other objects and aims of the invention, more or less specific than those referred to above, will be in part obvious and in part pointed out in the course of the following description of the elements, combinations, arrangements of parts and applications of principles, constituting the invention, and the scope of protection contemplated will be indicated in the appended claims.

In the accompanying drawing wherein I have illustrated a preferred form of embodiment of my invention,

Figure 1 is a view in perspective illustrating the manner in which my improved terrazzo strip is employed in terrazzo floor construction, a part of the floor being broken away better to illustrate the invention,

Figure 2 is a top plan view showing two intersecting strips of my improved construction and also showing the means employed for securing and locking together the abutting strip sections,

Figure 3 is a vertical sectional view taken substantially on the line 3—3 of Figure 2, assuming that said line is extended to the end of the construction shown in Figure 2,

Figure 4 is a side elevational view of one of my improved terrazzo strips, broken away so that the construction of the end of the strip may be illustrated,

Figure 5 is a top plan view of a portion of one of the strips showing the flanged construction thereof, and

Figure 6 is a vertical sectional view taken through the flanged part of the strip showing the manner in which the strip is fastened to the underlying floor.

Referring now to the drawing wherein similar reference characters refer to separate parts throughout the several views of the drawing, the reference numeral 1 denotes my improved strip, formed of metal, preferably brass.

It will be noted that the upper edge 2 of this strip is perfectly straight and is unbroken throughout its entire extent as illustrated in Figure 1.

The reference numeral 3 denotes a pair of flanges which are struck out from the material of the strip so that each flange stands out from the strip, the flanges of each pair forming an oblique angle with the plane of the side of the strip and the ends of said flanges being slightly

spaced apart as at 4, the width of said spaces being preferably slightly less than the thickness of the material forming the strip.

The reference numeral 5 indicates another pair of flanges struck out in an opposite direction from the strip, said last named flanges being also similarly spaced apart at their ends as at 6.

By reference to Figures 1, 3 and 4, it will be seen that the flanges of each adjacent pair are 10 located in different vertical planes, that is to say, one pair of these flanges is located in a higher plane than the other pair of neighboring flanges. The members of each neighboring pair of flanges are struck out in opposite directions from the 15 metal composing the strip and the spaces or recesses 4 and 6 between the ends of the flanges are disposed in opposite relations.

The width of the bases of the opposed flanges together, in practice, equal one-half of the width 20 of the strip for reasons which will be apparent hereinafter.

The flanges are preferably equidistantly spaced along the length of the strip and are also preferably disposed alternately on the opposite side 25 of the strip as shown in the full and dotted lines in Figures 3 and 4 of the drawing.

The reference numeral 7 denotes a plurality of preferably circular apertures which are equidistantly disposed throughout the length of the strip 30 and the lowermost part of the edges of each of these apertures are located at a distance one-half way through the width of the strip. These apertures 7 permit the plastic material to flow through them, thus establishing a bonding relation 35 between the plastic material on the opposite sides of the strip, and they have a further function which will now be described. The apertures 7 as aforesaid are formed in the strip when the same is originally produced. In the manipulation 40 of the strips in the forming of the pattern for the finished floor, the mechanic employed to lay the strips cuts a recess such as shown at 8 directly above one of these recesses where strips are to cross each other. This recess or slot together 45 with the recess 7 into which it leads permits these cross strips at their point of intersection to be relatively engaged in such a way that the upper edges of the strips at their point of intersection will lie in the same plane. This 50 also is accomplished by reason of the fact that the bases of the flanges 7 occupy half of the width of the strip and the recess 8 and the aperture 7 into which said recess leads occupy half of the width of the strip.

Each strip at one end is provided with a plurality of fingers and these fingers are extended alternately in opposite directions, the sides of the fingers lying in a plane parallel with the plane of the strip as shown in Figure 1 of the drawing. 55 In the present instance, two pairs of fingers No. 9, 9¹ and 10, 10¹ are shown at one end of the strip, each pair being disposed in a direction opposite to that of the others. By reference to Figure 3 of the drawing it will be noted that the uppermost 60 of one of said flanges 10 has been cut off leaving a stub which will be abutted by the plain end of the adjacent strip. By means of this construction it will be noted that the forked end of the strip will not be visible from the outer surface of the 65 flooring and that merely the abutting ends of the adjoining strips will be visible upon the exterior surface of the flooring.

The lateral spaces between the fingers are slightly less than that of the width of the strip 70 so that when the plain end of one strip is inserted

between the fingered end of its neighboring strip a resilient frictional engagement will be established between the neighboring ends, thus facilitating the holding together of the framework formed by the strips during the laying of the 5 plastic material.

Referring now to Figure 6 of the drawing, it will be noted that the flanges 3 form an opening 11 between them and similarly the flanges 5 provided upon the opposite side of the strip form 10 an opening 12, and that these two openings form an oblique passageway through which a nail 13 or other fastening device may be inserted and driven into the surface underlying the plastic or terrazzo floor. This nail 13 or other fastening 15 device serves to anchor the strip framework to the floor.

If desired, I may press portions of the material of the strip in an outward direction as shown at 14 which serve as additional anchorage for 20 the plastic material lying within the framework formed by the strips and these pressed-out formations may be of any desired design which, aside from their mechanical construction, may operate as a trade-mark. For instance, as shown 25 herein these pressed-out portions are intended to simulate a pine tree.

In the present instance the head 15 of the nail 13 may have its circular edges cut away at one point in its circumference providing a flattened 30 portion which lies in engagement with the side wall of the strip, thus making it possible for the head of the nail to be driven through into the underlying surface.

Having thus described my improved terrazzo strip, the manner of using the same which should be largely obvious from the above description is substantially as follows: It is understood that while I have shown herein a wooden floor upon 35 which the plastic or terrazzo flooring is to be 40 laid, this underlying surface may be formed of other materials or in fact any material into which an anchoring member such as a nail may be driven.

The fact that the lowermost flanges 3 formed 45 on the lower edge of the strip are disposed alternately in opposite directions a construction is provided whereby each strip will stand alone without any additional support, the oppositely disposed flanges serving as feet to hold the strip 50 in a vertical direction. The provision of the aperture 7 enables the mechanic engaged in laying the floor to provide points of intersection between crossed strips at any desired location along the length of a strip. This is accomplished as 55 above described by merely slotting the material of the strip in a downwardly direction directly above one of these openings 7.

Referring to Figures 1 and 2 of the drawing it will be noted that the ends of the flanges engaging 60 the cross strip braces the latter and tends to hold it in a vertical position. Thus the strips at their 65 points of intersection mutually brace each other and in that way serve to hold the members of the entire floor framework in firm engagement, insuring against displacement of any part of this framework during the laying of the floor.

Inasmuch as the slot 8 which is cut by the workman, at the point of intersection of cross strips is filled by the material of the strip entering 70 the slot, there is an unbroken metallic surface throughout the finished floor, in other words the pattern formed by the upper edges of the strips which lie flush with the surface of the floor is unbroken throughout its entire extent.

It will be obvious, of course, that instead of providing the nail 13 diagonally or obliquely into the floor, a nail may be inserted in a vertical direction through each of the spaces 11 and 12 formed by their respective flanges.

It will accordingly be seen that I have provided a construction well adapted to attain, among others, all the ends and objects of the invention in a most facile manner. The opposed flanges provide a means for effectually fastening the individual strips as well as the entire frame work formed by said strips and the underlying surface, and these flanges have a further function of providing spaces into which the plastic material flows thereby increasing the anchorage between the plastic material and the strips. The apertures 7 also serve to increase the bonding of the plastic material at opposite sides of the strip.

As many changes could be made in this construction without departing from the scope of the following claims, it is intended that all matter contained in the above description or shown in the accompanying drawing shall be interpreted as illustrative only and not in a limiting sense.

Having thus described my invention what I claim as new and desire to secure by Letters Patent is:

1. A dividing strip for sectional plastic floor construction comprising a strip of flexible metal having an unbroken upper edge, a plurality of flanges struck out from the material of the strip at its lower edge and extending laterally, obliquely in one direction and a plurality of flanges struck out from the material of said strip directly above said first named flanges and extending outwardly, obliquely in an opposite direction, the distance separating the edge of said flanges being equal to the thickness of the strip.

2. In sectional plastic flooring, a dividing strip for said plastic sections comprising a strip of flexible metal having an unbroken upper edge and two pairs of free ended flanges struck out from the material of the strip at its lower edge, one pair of said flanges extending outwardly, obliquely in one direction, the other pair of said flanges extending outwardly, obliquely in another direction, said free ended flanges having a slot between them of a width substantially equal to the thickness of the strip.

3. In sectional plastic flooring, a dividing strip for said plastic sections comprising a strip of flexible metal having an unbroken upper edge and two pairs of flanges struck out from the material of the strip at its lower edge, one pair of said flanges extending outwardly, obliquely in one direction and the other pair of said flanges extending outwardly, obliquely in another direction, the combined width of said flanges being equal to one-half of the width of the strip, the distance between the ends of flanges being substantially equal to the thickness of said strip.

4. A device of the class described comprising a strip of flexible metal having an unbroken edge, a pair of flanges struck out from the material of the strip and extending outwardly at an oblique angle to the strip and breaking the lower edge thereof, a pair of flanges struck out from the material of the strip and located directly above said first named flanges and extending outwardly at an oblique angle to the strip, the ends of said flanges being spaced apart a distance substantially equal to the thickness of the strip.

5. In plastic floor construction, a strip of flexible metal having an unbroken upper edge, a pair of straight flanges struck out from the material

of the strip at the opposite edge of said strip and extending outwardly toward each other and lying in an oblique angle with respect to the side of the strip, a pair of flanges struck out from the material of said strip and located immediately above said first named flanges and extending in an opposite direction at an oblique angle to the side of the strip, the combined width of said flanges being equal to one-half the width of the strip, the spaces between the ends of opposing flanges being substantially equal to the thickness of said strip, a plurality of apertures formed in said strip, the lowermost edge of said apertures being located midway of the width of said strip and the material of said strip being adapted to be slotted directly above any one of said apertures.

6. In sectional plastic floor construction a strip of flexible metal having an unbroken upper edge, a plurality of free ended flanges struck out from the body of the strip at its lower edge extending outwardly from the body of the strip in one direction and a plurality of free ended flanges located directly above said first named flanges and extending outwardly from the body of the strip in another direction, said flanges forming partly closed spaces and said spaces forming an oblique passageway through which a nail or other fastening device may be inserted whereby to secure said strip to an underlying surface.

7. A dividing strip adapted for use in plastic floor construction comprising a strip having a straight upper edge and a broken lower edge formed by a plurality of free ended flanges struck out from the material of the strip and extending in opposite directions from the body of the strip, said flanges being disposed in alternate relation throughout the length of the strip, and the ends of said flanges being spaced apart to form a slot substantially equal to the width of the strip.

8. A strip for providing a dividing means for plastic sectional floor construction having a straight unbroken upper edge, a plurality of flanges struck out from the material of the strip at its opposite edge, said flanges extending outwardly and obliquely with respect to the sides of the strip, a pair of flanges struck out from the body of the strip and located immediately above said first named flanges and extending outwardly from the body of the strip in a direction opposed to that of the direction of the first named flanges, each pair of flanges approaching each other to form a narrow passageway having a width substantially equal to the thickness of the strip and said passageways being disposed opposite each other along a plane at right angles to the length of the strip.

9. As a new article of manufacture, a strip of flexible material for use in sectional plastic flooring having a width equal to the thickness of the floor to be laid and having an unbroken upper edge and a plurality of flanges struck out from the material of the strip at its lower edge and extending outwardly in one direction, said flanges being arranged in alternate relation throughout the length of the strip, a plurality of flanges struck out from the body of the strip and located directly above said first named flanges and extending outwardly in another direction with respect to the strip the space separating opposing flanges being substantially equal to the thickness of the strip, said last named flanges being disposed in alternate relation throughout the length of the strip and said strip having a plurality of apertures cut through the material of the strip

and located intermediately the neighboring pairs of flanges.

10. A dividing strip for sectional plastic flooring composed of a strip of flexible metal having means for forming a binding engagement with the plastic material, said means being adapted to receive a nail or other device for fastening said strip to an underlying surface and a plurality of opposed fingers formed on one end of said strip, 5 the opposite end of said strip being plain whereby it may be engaged with the opposed fingers of a neighboring strip, the uppermost finger of one of said strips being cut off forming a stub which will be abutted directly by the plain end of its 10 neighboring strip.

11. In plastic sectional floor construction a plurality of strips of flexible metal, each of which is provided with a plurality of opposed angles at its lower edge, said flanges approaching each other 20 to form a passageway between the ends thereof on opposite sides of the strip, said passageway being located in a plane at right angles to the strip, each of said strips having a plurality of openings located intermediately of its flanges and 25 each of said strips being adapted to be slotted directly above any one of said apertures whereby to receive the flanged portion of another strip whereby two of said strips may be mutually engaged with each other at their point of intersection. 30

12. In plastic sectional floor construction a

plurality of strips of flexible metal, each of which is provided with a plurality of opposed flanges at its lower edge, said flanges approaching each other to form a passageway between the ends thereof on opposite sides of the strip, said passageway being located in a plane at right angles to the strip, each of said strips having a plurality of openings located intermediately of its flanges and each of said strips being adapted to be slotted directly above any one of said apertures whereby 10 to receive the flanged portion of another strip whereby two of said strips may be mutually engaged with each other at their point of intersection, and the ends of the flanges of one strip engaging with the side of the intersecting strip to 15 form bracing means therefor.

13. In sectional plastic floor construction, a dividing strip for said plastic floor sections comprising a strip of flexible material having an unbroken upper edge, a pair of free ended flanges 20 struck out from the material of the strip and extending outwardly, obliquely in one direction, and a pair of free ended flanges struck out from the material of said strip and extending outwardly obliquely in another direction, said flanges 25 being disposed in alternate relation throughout the length of the strip, and the opposite flanges of each pair having a slot between their ends of sufficient width to receive a cross strip between them. 30

ORRIL H. HAYES.
